HYDROCARBON TREATING PROCESS

Robert A. Woodle, Nederland, Tex., assignor to Texaco Inc., New York, N.Y., a corporation of Delaware
Filed May 28, 1964, Ser. No. 370,982
4 Claims. (Cl. 208—313)

This application is a continuation-in-part of application Serial No. 124,839 filed July 18, 1961 now Patent 3,167,501.

This invention is directed to a hydrocarbon treating process. More particularly, it relates to a method of refining a hydrocarbon oil by liquid-liquid solvent extraction employing furfural as a solvent.

In accordance with the process of this invention, a hydrocarbon oil boiling within the range of about 250 to 600° F. is contacted with a solvent comprising furfural and containing at most about 0.5 weight percent dissolved water, and furfural is separated from the resulting raffinate and extract-mix phases by distillation in the absence of added steam. Separation of furfural from the raffinate is effected by an azeotropic distillation employing hydrocarbon separated from the hydrocarbon oil feed as an azeotrope former. Furfural is separated from the extract-mix by extractive distillation in the presence of a relatively high boiling hydrocarbon oil effecting separation of furfural distillate substantially free of hydrocarbon. Extractive distillation bottoms are stripped to separate extract and any remaining furfural from the heavy hydrocarbon oil which is returned to the extractive distillation tower. Extract stripped from the heavy hydrocarbon is separated from any remaining furfural by distillation in an azeotropic distillation zone employing hydrocarbon separated from said extract as azeotrope former.

In solvent refining processes where the solvent and material treated have substantially different boiling ranges, the solvent is readily separated from the extract and raffinate phases by simple distillation. However, separation by simple distillation is incomplete when the oil treated contains components having true boiling points in the region of the boiling range of the solvent. In my co-pending application, Serial No. 124,839, filed July 18, 1961 of which this application is a continuation-in-part, I have described a method of treating hydrocarbon stocks containing components co-boiling with the solvent employing azeotropic distillation with steam to separate solvent from the raffinate and extractive distillation and steam stripping to separate solvent from the extract-mix. When the furfural solvent is separated by stripping or azeotroping with steam, the recovered solvent is saturated with water. (Furfural containing dissolved water in excess of about 0.5 weight percent is referred to hereinafter as wet.) When employing wet furfural for extraction, the solubility of hydrocarbons is markedly reduced so that considerably higher solvent dosages and higher temperatures must be employed to obtain the same yields upon extraction. If high dosages are to be avoided, wet furfural must be subjected to further distillation for separation of the dissolved water. I have now found that the solvent may be separated from the extract-mix and from the raffinate by distillation in the absence of added steam by employing a part of the hydrocarbon feed stock as an azeotrope former. Furfural and hydrocarbon boiling within the range of about 200 to 430° F. form azeotropes with furfural. These azeotropes are lower boiling than either furfural or the specific hydrocarbon species present in the azeotrope and are heterogenous, that is, upon condensation, they form separate hydrocarbon and furfural phases. The separated furfural phase may be returned to the extraction system and the separated hydrocarbon phase may be returned to the azeotropic distillation to supply the entire

2

requirement of azeotrope former. In this way furfural is separated free of water and at the same time, the hydrocarbon product is effectively stripped of furfural.

It is an object of this invention to provide a means of 5 treating hydrocarbons boiling within the range of about 250 to 600° F. and containing a substantial portion of hydrocarbons boiling less than 430° F. with furfural as a solvent. It is a further objective of this invention to provide a means of treating such hydrocarbons with furfural and distillatively separating the furfural from the resulting extract-mix and the raffinate by distillation in the absence of steam whereby the furfural is separated in the substantial absence of dissolved water. An advantage of the 10 process of this invention is that the solvency of the furfural is maintained at a high level whereby the solvent dosage may be maintained at a reasonably low level. Other 15 objects and advantages will be apparent from the following description and claims.

In the solvent extraction step of this process, the principal variables in the process are: charge stock boiling 20 range, extraction temperature, and solvent dosage. Since the solvent removal from both the refined oil and extract oil ultimately depend upon formation of binary hydrocarbon-furfural azeotropes from the hydrocarbons present 25 in the feed stock itself, it is important that the charge stock have an initial boiling point of at least 200° F., and preferably of at least 250° F. to exclude lower-boiling non-azeotroping hydrocarbons. The charge stock boiling range should be limited to an end point of about 600° F. 30 to insure easy separation from the heavy paraffinic oil used as extractive distillation solvent. Extraction temperatures are limited to temperatures below the miscibility point for the particular solvent dosage being used. Preferred temperatures are in the range from 90° F. to 170° F. Preferred solvent dosages are in the range from 50 to 350 35 volume percent basis charge oil.

In the azeotropic distillation of the raffinate-mix, the principal feature of this invention is that the azeotrope former is a portion of the hydrocarbon feed and the 40 amount of azeotrope former required is supplied by recycling separated distillate in a quantity sufficient to satisfy the requirements for the azeotrope former. By returning all of the hydrocarbon separated as distillate to the distillation zone, the entire requirement of hydrocarbon to strip 45 all of the furfural out of the raffinate is obtained. This hydrocarbon is returned to the distillation tower as reflux and the distillation can therefore be operated with no net hydrocarbon distillate production and all of the refined oil stripped of furfural is withdrawn as bottoms from the 50 azeotropic distillation tower.

In the extractive distillation step of this invention, distillative separation of solvent from dissolved hydrocarbon is effected in the presence of a relatively high-boiling hydrocarbon oil. The presence of the high-boiling oil reduces the relative volatility of the co-boiling components 55 of the dissolved oil so that solvent free of co-boiling hydrocarbons is removed as distillate and all of the oil initially dissolved in the solvent is removed as bottoms with the relatively high-boiling oil. The extractive distillation 60 is effected at a pressure selected to augment the effect of the high-boiling oil on the relative volatility of the co-boiling hydrocarbon and to achieve optimum and most economical equipment design and operation. Preferred pressures in the extractive distillation step may be within the range of less than atmospheric, that is, a vacuum, up to about five atmospheres or higher. The relatively high-boiling oil itself should be free of components boiling in 65 the region of the solvent and preferably should consist of components having true boiling points at least 100° F. above the boiling range of the solvent. Additionally the high-boiling oil should consist of components boiling wholly above the treated oil. When treating oil boiling 70

within the range of 250 to 600° F., with dry furfural which boils at 323° F., it is preferred to employ a paraffinic oil boiling wholly about 700° F. at atmospheric pressure. Suitable high-boiling oils include both distillates and residual oils. In the extractive distillation step, it is frequently advantageous to separate a major portion of the furfural as distillate leaving a minor portion of the furfural in the bottoms to prevent carryover of the oil being treated. In this case, the furfural is removed as distillate when stripping the extract from the heavy oil. The furfural then is separated from the extract by a further distillation employing the oil constituents as azeotrope formers so that this furfural is also separated in the absence of added water.

The accompanying drawing diagrammatically illustrates one embodiment of the process of this invention. Although the drawing illustrates an arrangement of apparatus in which the process of this invention may be practiced, it is not intended to limit the invention to the particular apparatus or materials described.

Referring to the figure, a hydrocarbon stock consisting predominantly of hydrocarbons boiling in the range of 250 to 600° F. is charged through line 1 to extraction tower 2. In extraction tower 2, the oil is countercurrently contacted with solvent introduced into the top of tower 2, through line 3. Raffinate-mix, comprising refined oil and a small amount of dissolved solvent, is withdrawn through line 4 and passed to distillation column 7. Since the refined oil itself is comprised largely of hydrocarbons which form binary azeotropes with furfural, the overhead vapor from column 7 consists of azeotropes of furfural with hydrocarbons occurring naturally in the extraction charge stock, thereby removing all of the solvent in the azeotropic mixture withdrawn as distillate through line 10. Refined oil free of solvent is withdrawn from the bottom of tower 7 through line 11.

The azeotropic mixture comprises vapors of solvent and a small amount of hydrocarbon oil. The vapor mixture is condensed in cooler 15 and the resulting condensate is passed through line 16 to separator 17. Two liquid phases separate, that is an oil phase (lighter) containing a small amount of dissolved solvent and a solvent phase (heavier) containing a small amount of dissolved oil. Separated solvent phase is withdrawn through line 20 and returned to extraction tower 2 through line 3. Separated oil phase is withdrawn through line 22 and is returned, at least in part, to tower 7 as additional azeotrope-forming reflux.

Extract-mix is withdrawn from extraction tower 2 through line 32, heated in heater 46 and passed through line 49 to extractive distillation tower 50.

In extractive distillation tower 50, the hydrocarbon and solvent vapors are distilled in contact with a relatively high boiling hydrocarbon oil introduced into the top of tower 50 through line 55. By distilling the solvent and extract vapors in contact with the high-boiling oil, the extract vapors are condensed in the high-boiling oil and solvent essentially free of oil is removed as distillate through line 56, condensed in cooler 23 and run to solvent storage drum 25 through line 24. The extractive distillation tower bottoms, comprising the high-boiling oil, extract oil, and a part of the solvent, are withdrawn through line 57 and passed through heater 58 and line 59 to extract stripping tower 60.

In extract stripping tower 60, essentially all of the solvent contained in the heavy oil is distilled overhead as a binary azeotrope along with the extract oil. High-boiling oil is withdrawn from the bottom of tower 60 for recycle to extractive distillation tower 50 through line 55. Extract and solvent vapors removed as distillate from tower 60 are passed through line 65, cooler 66, and line 67 to separator 68. In separator 68, two liquid phases are formed. A heavier solvent phase comprising the solvent plus a small amount of dissolved oil is withdrawn through line 76 and is returned to the extract-mix line 32. A lighter oil phase comprising the extract oil plus a small

amount of dissolved solvent is withdrawn through line 72 and passed through heater 73 into azeotropic distillation tower 80.

Since the extract oil itself is comprised largely of hydrocarbons which form binary azeotropes with furfural, the overhead vapor from column 80 consists of azeotropes of furfural with hydrocarbons occurring naturally in the extraction charge stock. All of the solvent charged to column 80 is withdrawn with the distillate as an azeotropic mixture, through line 81. Extract oil free of solvent is withdrawn from the bottom of tower 80 through line 82.

The azeotropic mixture comprises vapors of solvent and a small amount of hydrocarbon oil. The vapor mixture is condensed in cooler 90 and the resulting condensate is passed through line 91 to separator 92. Two liquid phases separate, that is an oil phase (lighter) containing a small amount of dissolved solvent and a solvent phase (heavier) containing a small amount of dissolved oil. Separated solvent phase is withdrawn through line 93 and returned to the extract-mix line 32. Separated oil phase is withdrawn through line 94 and is returned to column 80 as additional azeotrope-forming reflux.

Example 1

The following example illustrates the application of the process of this invention to the refining of a kerosene stock useful in the manufacture of jet fuel. In the following example, flow rates are expressed in terms of liquid barrels per hour regardless of whether the particular stream is in the liquid or vapor form.

A kerosene stock having an ASTM distillation initial boiling point of 316° F., a 50 percent point of 407° F., and an endpoint of 502° F. at a rate of 10 barrels per hour is countercurrently contacted with 14.8 barrels per hour of solvent having a composition of 94.2 percent furfural, 5.8 percent dissolved oil and less than 0.1 percent dissolved water. Extraction is effected with a top tower temperature of 120° F. and a bottoms tower temperature of 130° F. Raffinate mix at a rate of 8.8 barrels per hour is distilled at a top tower temperature of 348° F. to produce 8.2 barrels per hour of oil bottoms free of solvent and an overhead azeotropic distillate. The azeotropic distillate is condensed separating 0.6 barrels per hour of solvent phase comprising 93 percent furfural and 6 percent oil, and 12.9 barrels per hour of oil phase comprising 93 percent oil and 7 percent furfural. The solvent phase is returned as part of the solvent passed to the extraction tower. The oil phase is returned as reflux to the raffinate mix fractionator.

Extract-mix at a rate of 16.0 barrels per hour comprising 83 percent furfural and 17 percent oil together with 0.2 barrels of recovered solvent as hereinafter provided comprising 93 percent furfural and 7 percent oil is heated to 325° F. and passed to an extractive distillation tower operated at 9 p.s.i.g. and a top tower temperature of 351° F. A heavy paraffinic distillate oil boiling wholly above 760° F. at atmospheric pressure is refluxed to the top of the extractive distillation tower at a rate of 26.6 barrels per hour. Extractive distillation tower overhead at a rate of 14.2 barrels per hour comprising 94.2 percent furfural and 5.8 percent oil is condensed and passed to a solvent supply tank.

Extractive distillation tower bottoms, at a rate of 28.6 barrels per hour comprising 93 percent heavy oil, 0.7 percent furfural and 6.3 percent extract oil is heated to 600° F. and passed to an extractive solvent stripper, to recover 26.6 barrels per hour of heavy oil as bottoms for recycle to the extractive distillation tower and 2.0 barrels per hour of distillate. Distillate is condensed to form an oil phase comprising 90 percent extract oil and 10 percent furfural.

Distillate from the extractive distillation is charged at a rate of 2.0 barrels per hour to an extract oil azeotropic distillation tower at a pressure of 10 p.s.i.g. and a

top tower temperature of 329° F. to produce 1.8 barrels per hour of furfural free bottoms and 2.20 barrels per hour of distillate. This distillate is condensed and separated into a heavy furfural phase comprising 93 percent furfural and 7 percent oil, and a lighter oil phase comprising 93 percent oil and 7 percent furfural. The oil phase is returned to the azeotropic tower as reflux. The solvent layer is returned to the extract-mix stream leaving the extractor.

A comparison of tests on the charge kerosene and on the refined kerosene from the operation as described above is shown in Table I:

TABLE I

	Charge	Refined Oil	15
Refractive Index at 70° C.	1.4250	1.4186	
Hydrocarbon Analysis, Vol. Percent:			
Total Aromatics	14.0	5.0	
Olefins	0.9	0.7	
Dinuclear Aromatics, Wt. Percent	2.3	0.11	20
Smoke Point, mm. (ASTM Designation D-1322)	25	35	
Luminometer No. (ASTM Designation D-1740)	58	77	

The results demonstrate the effectiveness of the process for removing aromatics and improving the smoke point, luminometer number, and dinuclear aromatics values.

Example II

In another example of the process of this invention, a catalytically cracked light cycle gas oil is refined reducing the aromatic content and carbon residue. For comparison, the same oil is refined by an analogous procedure except that the furfural is separated from the resulting raffinate and extract-mix phases by steam stripping and contains about 5.0 weight percent water. The results of this comparison are shown in Table II.

TABLE II

	Furfural stripped with steam	Furfural stripped with hydrocarbon azeotrope	40
Charge Stock Tests:			
RI at 70° C.	1.4890		
Gravity, ° API	27.2		
Carbon Residue, 10% bottoms, Wt. Percent	0.48		
Aromatics, Vol. Percent	55.9		45
ASTM Distillation, ° F.:			
IBP	392		
10	466		
50	484		
90	520		
EP	566		50
Rates, cc./hr.:			
Charge Oil	7,522	9,850	
Furfural	13,060	10,400	
Solvent Dosage, Vol. Percent	200	106	
Water Content of furfural, Wt. Percent	5.0	0.5	
Temperatures, ° F.:			
Raffinate outlet	119	120	55
Extract-mix outlet	94	92	
Oil in Extract-mix, Vol. Percent	20.5	39.0	
Yield of Refined Oil, Vol. Percent	54.6	67.3	
Refined Oil Tests:			
RI at 70° C.	1.4395	1.4387	
Gravity, ° API	40.5	41.8	
Color, ASTM	less than	less than	
Sulfur	2.0	1.5	60
Carbon Residue, 10% Bottoms, Wt. Percent	0.09	0.07	
Aromatics, Vol. Percent	20.8	17.8	

It will be noted from the above comparison that dry furfural (containing 0.5 weight percent dissolved water) at comparable extraction temperatures produces an appreciably higher yield of somewhat superior refined oil and with a solvent dosage of only about half that needed using wet furfural. The higher oil content of the extract-mix with dry solvent, 39.0 as compared with 20.5, shows the superior oil-carrying power of dry furfural over wet furfural.

I claim:

1. In the solvent refining of a hydrocarbon oil boiling

within the range of about 250 to 600° F. and having an ASTM distillation 50 percent point less than 430° F. wherein said hydrocarbon oil is contacted with a solvent comprising furfural forming raffinate and extract-mix phases and refined oil and extract are separated from said raffinate and extract-mix phases respectively, the improvement which comprises:

contacting said hydrocarbon oil with a solvent consisting essentially of furfural and containing at most about 0.5 weight percent dissolved water forming raffinate and extract-mix phases,

separating said phases, distilling said raffinate phase in the presence of a hydrocarbon azeotrope former separated from said raffinate and in the absence of added steam in a distillation zone separating an azeotrope of furfural and hydrocarbon as distillation vapors from refined oil as distillation bottoms,

condensing said distillation vapors forming a hydrocarbon phase and a furfural phase, and passing at least a part of said hydrocarbon phase to said distillation zone as said hydrocarbon azeotrope former.

2. In the solvent refining of a hydrocarbon oil boiling within the range of about 250 to 600° F. and having an ASTM distillation 50 percent point less than 430° F. wherein said hydrocarbon oil is contacted with a solvent comprising furfural forming raffinate and extract-mix phases and refined oil and extract are separated from said raffinate and extract-mix phases respectively, the improvement which comprises:

contacting said hydrocarbon oil with a solvent consisting essentially of furfural and containing at most about 0.5 weight percent dissolved water forming raffinate and extract-mix phases,

separating said phases, distilling said raffinate phase in the presence of a hydrocarbon azeotrope former separated from said raffinate and in the absence of added steam in a first distillation zone separating an azeotrope or furfural and hydrocarbon as distillation vapors from refined oil as distillation bottoms,

condensing said distillation vapors forming a hydrocarbon phase and a furfural phase, passing at least a part of said hydrocarbon phase to said first distillation zone as said hydrocarbon azeotrope former,

distilling said extract-mix phase in the presence of an added high boiling oil having an ASTM initial boiling point of at least 625° F. and in the absence of added steam in a second distillation zone separating furfural substantially free of oil as distillation vapors from distillation bottoms comprising said high boiling oil and extract hydrocarbons, and

distilling said distillation bottoms from said second distillation zone in the absence of steam in a third distillation zone separating said extract as distillate from said high boiling oil.

3. The process of claim 2 wherein the distillate from said third distillation zone comprises extract hydrocarbons and furfural and said extract and furfural are separated by an azeotropic distillation in a fourth distillation zone.

4. The process of claim 3 wherein the azeotropic distillation in said fourth distillation zone is effected in the presence of a hydrocarbon azeotrope former separated from said extract.
